Primary Examiner — Garth Rademaker*Assistant Examiner* — Melanie Pellegrini(74) *Attorney, Agent, or Firm* — Lucas & Mercanti, LLP.(57) **CLAIM**

The ornamental design for a chain for necklaces or bracelets, as shown and described.

DESCRIPTION

FIG. 1 is a perspective view of a chain for necklaces or bracelets showing my new design;

FIG. 2 is a top view thereof;

FIG. 3 is a front view thereof;

FIG. 4 is a right side view thereof, the left side being a mirror image;

FIG. 5 is another perspective view thereof, with the cube-shaped element placed in a second position along the chain in order to show that it is slideable;

FIG. 6 is a top view thereof; and,

FIG. 7 is a front view thereof.

1 Claim, 2 Drawing Sheets(56)
